(57) **CLAIM**

The ornamental design for a tool-less terminal connector for side mount-type battery, as shown.

DESCRIPTION

FIG. 1 is a bottom left isometric view of a tool-less battery sidemount terminal connector, showing my new design;

FIG. 2 is a left end view thereof;

FIG. 3 is a left side elevational view thereof, the right side elevational view being identical, but reversed end for end;

FIG. 4 is a right end view thereof;

FIG. 5 is a plan view thereof as viewed along section lines 5—5 of FIG. 3;

FIG. 6 is a bottom left isometric view of a second embodiment of my new design;

FIG. 7 is a plan view thereof as viewed along section lines 7—7 of FIG. 8;

FIG. 8 is a left side elevational view thereof, the right side elevational view being identical, but reversed end for end;

FIG. 9 is a right end view thereof; and,

FIG. 10 is a left end view thereof.
